HABERDASHERY HANGER

Earl B. Seeger, 2830 N. 40th St., Milwaukee, Wis.

Filed Apr. 28, 1960, Ser. No. 60,360

Term of patent 14 years

(Cl. D80—8)

FIG. 3

FIG.2

FIG. 1 is a front elevational view of a haberdashery hanger embodying my new design, the opposite side being substantially a mirror image thereof.

FIG. 2 is a right side elevational view thereof.

FIG. 3 is a horizontal cross-sectional view thereof taken on line 3—3 of FIG. 1.

I claim:

The ornamental design for a haberdashery hanger, as shown and described.
